UNITED STATES PATENT OFFICE.

RICHARD MILLER, OF NEW BERLIN, OHIO.

DESIGN FOR A HARNESS-SADDLE.

44,069.

Specification for Design.

Patented May 20, 1913.

Application filed February 5, 1913. Serial No. 746,383. Term of patent 7 years.

To all whom it may concern:

Be it known that I, RICHARD MILLER, a citizen of the United States, residing at New Berlin, in the county of Stark and State of Ohio, have invented a new, original, and ornamental Design for a Harness-Saddle, of which the following is a specification, reference being had to the accompanying drawing, forming part thereof.

In the drawing Figure 1 is a perspective

view of a harness saddle embodying my new design. Fig. 2 is a top-side plan view of the same.

I claim:—

The ornamental design for a harness saddle, substantially as shown.

RICHARD MILLER.
